UNITED STATES PATENT OFFICE.

FINN T. IRGENS, OF JACKSON, MICHIGAN, ASSIGNOR TO LOCKWOOD ASH MOTOR CO., OF JACKSON, MICHIGAN, A CORPORATION OF MICHIGAN.

OUTBOARD MOTOR.

Application filed December 14, 1925. Serial No. 75,278.

This invention relates to outboard motors which are ordinarily portable and adapted to be attached to the stern or transom of a boat or other water craft for propelling and 5 guiding the boat in a desired direction. Such a marine motor ordinarily includes an internal combustion engine and its necessary accessories, the engine being arranged so that its crank shaft or an extension thereof 10 may extend downwardly into a gear housing for driving a propeller. The gear housing usually includes a propeller guard and rudder, and the entire structure is mounted relative to a boat so that it may be adjusted. In 15 some instances a slip clutch is located in the gear housing to disconnect the propeller relative to its driving means when an obstruction is encountered, and in other instances the entire structure is pivotally 20 mounted so that the submerged end of the structure may yield and swing rearwardly when encountering an obstacle. Again, such marine motors are ordinarily supported so that the engine driven propeller may be 25 swung by a tiller for steering purposes.

In the above type of outboard motor I have made the following improvements.

First, I use a compact, durable and simple form of differential mechanism and clutch 30 by which the operation of the propeller may be reversed, so that a boat may be backed. If the outboard motor is of that type where the submerged end thereof may yield or swing rearwardly, it is necessary that means 35 be provided for holding the submerged end of the motor so that it cannot yield under a reverse operating condition of the propeller.

Second, I provide novel means in connection with the tiller of the outboard motor 40 for simultaneously operating the clutch for reverse drive and fix the submerged end of the motor against yielding because of such drive.

Third, my outboard motor includes certain refinements that will appear as the improvements are herein described by aid of 45 the drawings, wherein

Figure 1 is a side elevation of the outboard motor, partly in section;

Fig. 2 is an enlarged vertical sectional view of a portion of the outboard motor;

Fig. 3 is a horizontal sectional view taken on the line III—III of Fig. 2, and

Fig. 4 is a cross sectional view taken on 65 the line IV—IV of Fig. 3.

In the drawings, the reference numeral 1 denotes a vertically disposed sleeve bearing which is provided with apertured ears 2 pivotally connected, as at 3, to a clamping bracket 4 adapted to be attached to the stern 60 of a boat in the usual and well known manner.

Rotatable in the sleeve bearing 1 and supported thereby is a vertically disposed casing 5 having its lower end provided with a gear housing 6 from which is supported a driven propeller 7, a propeller guard 8, and a rudder 9, all of a conventional type and forming no part of this invention other than contributing to a complete outboard motor. 70 The upper end of the casing 5 is stepped so as to provide a spring chamber 10, a clutch chamber 11, and a differential chamber 12. On the upper end of the casing 5 and closing the differential chamber 12 is a cap or end 75 plate 13 that may form part of an internal combustion engine 14 having the usual accessories or auxiliary parts to provide a complete power plant. In the cap or end plate is a bearing and bushing 15 for a crank shaft 80 16 of the engine 14, and journaled in the end of the crank shaft and co-extensive thereof is a propeller driving shaft 17 disposed axially of the casing 5 and extending into the gear housing 6 for driving the propeller 7. 85

Mounted in the spring compartment 10 about the drive shaft 17 is a coiled expansion spring 18 seated on a retaining part 19 which is coupled to the shaft 17 and engages a wear plate 20 mounted in the compartment 90 10. The upper convolution of the expansion spring 18 engages a retaining member 21 on which is supported the bottom plate 22 of a hollow conical shaped clutch member 23 forming part of a differential housing 24 in 95 the compartment 12 and extending into the compartment 11 where said clutch member opposes and is surrounded by an outer stationary clutch member 25 detachably seated in the compartment 11 and retained therein 100 by suitable fastening means designated 26. The expansive force of the spring 18 holds the intermediate clutch member 23 out of engagement with the outer clutch member 25 and normally in engagement with a conical 105 shaped inner clutch member 27 having a sleeve portion 64 pinned or keyed to the drive shaft 17.

The inner clutch member 27 is made hollow to receive a differential gear 28 which 110

is keyed or otherwise fixed to the drive shaft 17 and meshing with the differential gear 28 are differential pinions 29 on a spider 30 through which extends the drive shaft 17. 5 Another differential gear 31 meshes with the differential pinions 29 and this differential gear is held against longitudinal movement relative to the differential pinions 29 and the shaft 17 by a collar 32 suitably fixed to 10 the shaft 17 and seated in a slotted hub portion 33 of the differential gear 31. The slotted hub portion 33 is loose in an end cap 34 of the housing 24 with the hub portion 33 surrounding a slotted extremity of the engine crank shaft 16, so that a driving relation may be established between the crank shaft and the differential gear 31 by interposed keys or coupling members 35 arranged in the slots of the hub 33 and the crank 20 shaft 16.

The casing 5, adjacent the end plate 13, is provided with transversely alining bearings 36 and 37 for an arcuated crank shaft 38 having crank portions 39 provided with 25 anti-frictional rollers 40 engageable with a wear plate 41 mounted on the differential housing cap 34. The crank shaft 38 is substantially made and has an end thereof provided with a rock arm 41 which is keyed or 30 otherwise non-rotatably connected to the crank shaft, as at 42. The arm is preferably hollow and its forward end is bifurcated and provided with a pin anchor 43 for the hook shaped end 44 of a detachable 35 lever or tiller 45, which may be disconnected from the arm 41 by swinging the tiller upwardly and disengaging the hook shaped end 44 from the anchor pin 43. Otherwise, the tiller 45 is supported co-extensive of the 40 rock arm 41 by the confronting ends of the arm and tiller.

On the side of the casing 5, adjacent the bearing 36 of the crank shaft 38, is a notched keeper 46 for a latch 47 pivotally mounted, 45 as at 48 on the arm 41 and extending therein, as best shown in Fig. 3. The inner end of the pivoted latch 47 is loosely connected to an actuating rod 49 slidably supported by the forward end of the arm 41 and protruding therefrom. The retractile force of a coiled spring 50 in the arm 41 is adapted to hold the latch 47 normally in one of the notches of the keeper 46.

The lever or tiller 45 has a handle 51 and 55 opposing said handle and cooperating therewith in providing a hand grip is a pivoted bell crank or handle 52 loosely connected to an operating rod 53 supported in the tiller 45 in abutting relation with the actuating 60 rod 49, so that these two rods may be shifted by the handle 52, against the expansive force of a small spring 54 between the handles 51 and 52 to shift the latch 47 out of engagement with the keeper 46 and permit of the 65 arm 41 being rocked.

The rear end of the rock arm 41 is pivotally connected, as at 55 to a depending rod 56 which has its lower end yieldably articulated with a fork 57 pivotally supported from the chamber portion 11 of the casing 5. The 70 fork 57 is loosely connected, as at 58 to the sides of a reciprocable sleeve 59 on the casing 5 and this sleeve is adapted to be shifted to extend over a semi-cylindrical abutment 60, loosely engaging the casing 5. The abutment 60 has side lugs 61 and set screws 62 extending into slotted segments 63 of the boat bracket 4, and it is by virtue of the set screws 62 that the outboard motor may be set at a desired angle relative to the boat 75 bracket. The lugs 61 prevent the abutment 60 from tilting relative to the segments 63 and with the casing 5 loose in the abutment it may swing rearwardly when encountering an obstacle during forward drive of the boat. 80

In operation the driving relation between the inner clutch member 27 and the intermediate clutch member 23 causes the drive shaft 17 to be driven in one direction from the crank shaft 16 of the engine 14 and this 90 direction is for normal straight ahead propelling of a boat equipped with the outboard motor. Should it be desired to reverse or back the boat, the tiller 45 is lowered to rock the crank shaft 38 and the fork 57. 95 Two adjustments are simultaneously made. The crank shaft 38 causes the differential housing 24 to be lowered against the action of the spring 18, thus bringing the intermediate clutch member 23 into engagement 100 with the stationary clutch member 25, whereby the differential housing will be held stationary causing the differential mechanism to reverse the rotation of the drive shaft 17. Since the propeller 7 will tend to pull the 105 submerged end of the outboard motor away from the boat, as when drawing the boat backwards, it is necessary that the abutment 60 be engaged by the sleeve 59, therefore adjustment of the fork 57 has lowered the 110 sleeve 59 into engagement with the abutment 60 and fix the submerged end of the outboard motor relative to the boat bracket.

As long as the tiller 45 is held depressed there will be a reverse drive and when the 115 tiller is released the expansive force of a spring 65 on the lower end of the rod 56 cooperates with the expansive force of the spring 18 in restoring the parts for forward drive.

My drawings have been copied from working drawings but I would have it understood that the structural elements are susceptible to such variations and modifications as are permissible by the appended claims. 125

What I claim is:—

1. In an outboard motor for a boat wherein an engine is adapted to drive a propeller by a drive shaft co-extensive of a crank shaft of the engine, and wherein a drive 130

- shaft casing is supported from a boat bracket and adapted to swing rearwardly to avoid an obstacle:—a differential mechanism for constantly meshing gears in said casing, a 5 clutch mechanism operatively arranged relative to said differential mechanism to afford normal forward boat drive for the propeller, and means adapted to simultaneously change the differential and clutch mechanism for 10 backward boat drive for the propeller and fix said casing against a rearward swing relative to said boat bracket.
2. In an outboard motor for a boat wherein an engine is adapted to drive a propeller 15 by a drive shaft, co-extensive of a crank shaft of the engine, and wherein a drive shaft casing is supported from a boat bracket and adapted to swing rearwardly to avoid an obstacle:—a differential and clutch 20 mechanism in said casing arranged to afford normal forward boat drive for the propeller, and means adapted to simultaneously change the differential and clutch mechanism for backward boat drive for the propeller and 25 fix said casing against a rearward swing relative to said boat bracket, said means including a tiller actuated reciprocable sleeve on the drive shaft casing.
3. In an outboard motor for a boat wherein 30 an engine is adapted to drive a propeller by a drive shaft, co-extensive of a crank shaft of the engine, and wherein a drive shaft casing is supported from a boat bracket and adapted to swing rearwardly to 35 avoid an obstacle:—a differential and clutch mechanism in said casing arranged to afford normal forward boat drive for the propeller, and means adapted to simultaneously change the differential and clutch mechanism for 40 backward boat drive for the propeller, and fix said casing against a rearward swing relative to said boat bracket, said means including a rock crank shaft adapted to depress a portion of said differential mechanism 45 and shift said clutch.
4. In an outboard motor wherein an engine crank shaft is adapted for driving a propeller drive shaft housed with a turnable casing:—means transmitting power from the 50 engine to the drive shaft, said means including a differential mechanism in said casing adjacent the upper end of said propeller drive shaft, a differential housing shiftable longitudinally of said casing, a clutch mechanism 55 in said casing operable by said shiftable differential housing for controlling the action of said differential mechanism for transmitting power, and means adapted for shifting said differential housing.
5. An outboard motor as called for in 60 claim 4 wherein said means includes a tiller adapted for either turning said casing or depressing said differential housing.
6. Means for transmitting power from an 65 outboard motor to a propeller wherein a pro-
- peller drive shaft is co-extensive of the motor shaft, said means comprising a differential mechanism operatively connecting said motor and propeller shafts, a clutch mechanism having as a shiftable element thereof 70 a part of said differential mechanism, and means adapted for controlling said clutch mechanism.
7. In an outboard motor for a boat wherein an engine is adapted to drive a propeller 75 by a drive shaft co-extensive of a crank shaft of the engine, and wherein a drive shaft casing is supported from a boat bracket:—means within said casing controlling the driving relation between the engine crank shaft and the drive shaft, said means including the differential mechanism and clutch mechanism about the drive shaft with the differential mechanism and clutch mechanism arranged for forward drive of 80 the propeller by the engine, said clutch mechanism including an intermediate clutch member adapted to be adjusted for holding a differential housing, and means carried by 85 said casing adapted for adjusting the intermediate clutch member.
8. In an outboard motor for a boat wherein an engine is adapted to drive a propeller by a drive shaft co-extensive of a crank 90 shaft of the engine, and wherein a drive shaft casing is supported from a boat bracket:—means within said casing controlling the driving relation between the engine crank shaft and the drive shaft, said means including the differential mechanism and clutch mechanism about the drive shaft with the differential mechanism and clutch mechanism arranged for forward drive of 95 the propeller by the engine, said clutch mechanism including an intermediate clutch member adapted to be adjusted for holding a differential housing, and means carried by 100 said casing adapted for adjusting the intermediate clutch member, said last mentioned means including a tiller arm adapted to 105 depress the differential housing and establish a reverse drive between the engine shaft and the drive shaft.
9. In an outboard motor having an engine 110 driven propeller supported from a casing braced for forward drive and normally free to swing rearwardly, engine driven forward and reverse power transmission mechanism in said casing, in closer proximity to the engine than to the propeller for normal forward drive, means operable to reverse the drive of the power transmission mechanism and to condition said casing for such reverse drive, said means including a stationary clutch member, a drive shaft clutch member, and an intermediate clutch member 115 shiftable between the first mentioned clutch members to afford either forward or reverse drive.
10. In an outboard motor having an en- 120

- gine driven propeller supported from a casing braced for forward drive and normally free to swing rearwardly, engine driven power transmission mechanism in 5 said casing for normal forward drive, and means operable to reverse the drive of the power transmission mechanism and condition said casing for such reverse drive, said means including a stationary clutch 10 member, a drive shaft member, and an intermediate clutch member shiftable between the first mentioned clutch members to afford either forward or reverse drive.
11. Means for transmitting power from an 15 outboard motor to a propeller, said means comprising a driven differential mechanism having constantly meshing gears, a movable housing for said differential gears adapted to be held for reversing the action of the 20 differential gears, and means adapted for holding said housing.
12. Means for transmitting power from an 25 outboard motor to a propeller, said means comprising a driven differential mechanism having constantly meshing gears adapted for two actions, a movable housing for said differential gears adapted to be held for changing from one action to the other of the differential gears, and means including 30 a clutch having a part thereof supported by said housing for holding said housing.
13. In an outboard motor mounted to be 35 horizontally turned by a tiller for steering purposes, and freely swung in a vertical plane when encountering an obstacle, and wherein an engine driven propeller is supported from a casing braced for forward drive;—engine driven power transmission mechanism in said casing for normal forward drive, and means operable by the 40 tiller to reverse the drive of the power transmission mechanism and condition said
- casing for reverse drive, said means including a reciprocable sleeve on said casing, and an arm linked with said sleeve and detachably supporting said tiller. 45
14. In an outboard motor wherein an engine crank shaft is adapted for driving a propeller drive shaft housed with a turnable casing:—means transmitting power from 50 the engine to the drive shaft, said means including a differential mechanism and clutch member, a differential housing having its lower end normally engaging said clutch member and by longitudinal movement 55 adapted to engage said casing, and rockable means in said casing engageable with the upper end of said differential housing adapted to move said housing.
15. An outboard motor as called for in 60 claim 14, wherein said differential and clutch mechanisms are disposed in said casing.
16. An outboard motor as called for in 65 claim 14, wherein said controlling means includes a detachable and depressible tiller articulated with said sleeve. 70
17. Means for transmitting power from an outboard motor to a propeller, said means comprising a driven differential mechanism 75 having constantly meshing gears adapted for forward and reverse actions, a movable housing for said differential gears adapted to be held for a reverse action of the differential gears, a clutch at one end of said housing and having a part thereof supported by said housing, and means at the opposite end of said housing adapted for moving said housing to effect holding thereof by said clutch. 80

In testimony whereof I affix my signature.

FINN T. IRGENS.
